BOX BLANK FOLDING MACHINE

Wilber E. Bowersock, Rochester, N. Y.

Application February 1, 1947, Serial No. 725,958

25 Claims. (Cl. 93—49)

1

This invention relates to machines for folding box blanks made of corrugated or other card-board material and, more particularly, to machines for folding the side portions or flaps of a scored blank inwardly and downwardly against its intermediate or body portion, in flat condition, with the edges in meeting relation for attachment to each other by stitching, taping, or the like.

The machines of the prior art have commonly involved the movement of the blank through the machine by feed rolls against stationary inclined forming guides for folding the side portions or flaps, with substantial resulting frictional resistance, requiring feed roll pressures tending to crush and injure the blank material. Other machines have employed cumbersome carrier chains for moving the blanks, or been lacking in speed and precision, or been subject to other objectional features. One object of the present invention, therefore, is to provide an improved machine of the above character having a more simple, practical and trouble-free type of construction.

The folding of such blanks has heretofore presented particular difficulties at the point at which the side portions or flaps are folded flat so as to bend the material sharply upon itself at an angle of about 180°, since the material becomes bunched in the bite of the bend and tends to deflect the line of bend out of the line of scoring provided for its guidance, with the result that the meeting edges are not parallel, or may even overlap, so as to produce an inaccurate box. Another object of the invention, therefore, is to provide an improved machine having means for positively controlling and confining the bending of the material to the score line provided to guide the folding and thus produce a more accurate box.

Another object is the provision of an improved machine capable of producing more accurately folded blanks at a higher rate of production.

A further object is to provide a machine capable of being more conveniently adjusted for the reception of blanks of varying sizes and shapes.

To these and other ends the invention resides in certain improvements and combinations of parts, all as will be hereinafter more fully described, the novel features being pointed out in the claims at the end of the specification.

In the drawings:

Fig. 1 is a top plan view of a machine embodying the present invention;

Fig. 2 is an enlarged side elevation of the same;

2

Fig. 3 is an end elevation as viewed from the left in Fig. 2;

Fig. 4 is a fragmentary perspective view, partly broken away, showing the blanks in successive stages of folding by a reciprocating blank pushing means, blank folding means and blank squaring and stripping means;

Fig. 5 is a fragmentary, perspective view of a modified form of blank squaring means;

Fig. 6 is a fragmentary top plan view of the blank guideway and pushing means;

Fig. 7 is a fragmentary side elevation of the same;

Fig. 8 is a section on the line 8—8 in Fig. 6;

Fig. 9 is a perspective view of a portion of a blank engaging member on the blank pushing means shown in Fig. 6;

Fig. 10 is a sectional elevation on the line 10—10 in Fig. 1 showing operating means for the squaring bar;

Fig. 11 is a sectional elevation on the line 11—11 in Fig. 1 showing a hopper gate finger and associated parts;

Fig. 12 is a section on the line 12—12 in Fig. 1 showing an adjustable hopper side flange, and

Fig. 13 is a sectional view on the line 13—13 in Fig. 11.

The embodiment of the invention herein disclosed, by way of illustration, comprises a machine having a main frame supported on four corner standards or legs 20, connected by upper side rails 21, lower side rails 22, upper end rails 23 and lower end rails 24, providing supports for other parts hereafter referred to. The front or

35 hopper end of the machine, shown at the top in Fig. 1 and at the right in Fig. 2, has on either side a pair of upwardly and outwardly extending braces 25 (Figs. 2 and 3), the upper ends of each pair of which support longitudinally extending

40 auxiliary rails 26 (Figs. 1 and 2), provided with rack bars 27. Heads 28 and 29 at opposite sides of the machine, respectively, are connected with each other and each encloses a pair of pinions (not shown) meshing with and rolling on the

45 racks 27 to support the heads for adjustment toward and from an inclined plate 30, forming the front wall of the hopper for a stack of blanks to be folded. Fixed to and connecting the heads is a transversely extending angle beam 31 (Figs. 1

and 2), and a transverse shaft 32 (Fig. 3) connects corresponding pinions in the heads to insure equalized movement of the heads and beam for varying the longitudinal dimension or length of the hopper. Head 29 comprises means, such as an electric motor 32a, for rotating shaft 32.

A scale 33 is provided on one of the rails 26 to indicate such adjustment.

The hopper width is controlled by side walls or flanges 34 carried by brackets 35 slidably lengthwise on beam 31 and each provided with a spindle 36 carrying a pinion meshing with rack bar 37 on the top of the beam, the upper ends of the spindles being provided with small hand wheels, as shown, for adjusting the side walls 34 toward and from each other in accordance with the width of particular blanks. Each bracket 35 carries a pointer, as 38, movable over a scale 39 on the beam to indicate the extent of adjustment, as further referred to hereafter. The bottom of the hopper is formed by a pair of outer bars 40 and a pair of spaced inner rails 41, both fixed on the main frame, the rails 41 extending longitudinally of the machine and forming a guideway over which the blanks are slidable through a feed gate on beam 31, as hereinafter described.

The height of the hopper feed gate above the guideway rails 41 is preferably adjusted by means comprising a plurality of pairs of rearwardly and downwardly inclined, gib-like plates 42 fixed to and supported on the front side of beam 31 (Figs. 2 and 11), each pair being located above one of the guide rails, 41. The plates in each pair are spaced for receiving and guiding therebetween a gate finger 43 the lower end of which is slidably retained between the gib plates by a bar 44 connecting the plates across the finger and by a bar 45 fixed to the finger and extending over the plates. The upper end of the gate finger is supported and adjusted by means comprising a bearing block 46 fixed on it and extending at its ends over the backs of the gib plates. Rotatably supported in each block is a spindle 47, the lower end of which is threadedly engaged in a hole in the beam 31. The upper end of each spindle is provided with a hand wheel 48, the rotation of which adjusts the gate finger toward and from the adjacent guide rail 41. Fixed on each finger is a resilient presser strip or shoe 49, in the nature of a leaf spring, the forward end of which is thus adjustably spaced from the adjacent guide rail 41, to correspond with the thickness of the blanks, by the above described adjustment of the finger gate, and the lower blank of the stack is fed, by means hereinafter described, through the gate and between the shoes 49 and the rails 41 on which they are slidably held by the shoes and the additional means hereinafter described. Shoes 49 may be connected with each other by an arched strap 49a, as shown, to preserve their alignment.

The means for feeding or moving the blanks comprises, preferably, an elongated, rectangular frame 50 (Figs. 1, 4 and 6), made of light metal tubing, with longitudinal side bars 51, connected centrally and at their rear ends by pairs of spaced cross bars 52 and 53, respectively. The forward ends of the side bars are connected by a plate 54, for a purpose hereinafter described, and the frame is stiffened by inclined braces 55. The side bars 51 are slidably supported and guided on gib, each comprising a brass angle bar 56 (Fig. 8), fixed to a brass plate 57 projecting at its upper edge above the bar 56 and both fixed to a structural bar 58 extending longitudinally between the upper end rails 23 of the frame and supporting the guide rails 41, the pusher frame being reciprocated on these gib by means hereinafter described.

At the forward end of the blank pusher frame, its transverse plate 54 carries a series of hinge

knuckles 59 between which are pivotally mounted three sheet metal dogs 60 having generally flat top surfaces and forward ends 61 turned downwardly for engagement with leaf springs 62 fixed on the frame bars 58, in the forward position of the dogs, as shown in Fig. 6, in which position the dogs are pressed upwardly, between and beside the guide rails 41, for engagement with the bottom of the stack of blanks in the hopper. The upper surface of each dog has fixed thereon a cleat 63, the edges of which are inclined upwardly and rearwardly, the rear edge having a series of teeth 64 for engagement in the interstices of a corrugated board between the facing sheets thereof, the cleat being of less thickness or height than the blank to be folded.

In the forward movement of the pusher frame, with the dogs 60 pressed upwardly by springs 62, the cleats 63 pass under and just beyond the stack of blanks and, on the return movement of the frame, engage the forward edge of the bottom blank and push it rearwardly through the hopper gate, the blanks above the lowermost one being retained by the gate fingers described above. As the dogs 60 move rearwardly out of engagement with the spring 62, they are held raised by engagement with the edge of the blank while the latter is being pushed to the first folding station. On the return movement 30 of the frame, however, the cleats 63 are disengaged from the blank and the dogs drop by gravity so as to pass under the blanks until again raised by the springs 62 for engaging and advancing the next blank to be folded.

Adjacent the longitudinal center of the pusher frame, a dog 65 has lugs 66 pivotally surrounding the forward cross brace 52, and the rear edge of the dog is bent downwardly to form a shoulder 67, the lower edge of which is partly curved forwardly, as at 68, for engagement under the adjacent cross brace 52 to limit the upward pivotal movement of the dog. A part of the lower edge of shoulder 67 is extended downwardly, as at 69, for engagement with a leaf spring 70 fixed at 71 on the beam 58 of the frame, for yieldably raising the dog to the position shown in Fig. 7 in the forward position of the pusher frame. The dog 65 is thus positioned for engaging the forward edge of a blank previously delivered to the first folding station by the dogs 60 and for pushing it rearwardly to a second folding station as the pusher frame is reciprocated toward the rear. During such movement the dog moves away from the spring 70 but is retained in elevated position by frictional engagement with the edge of the blank until disengaged by the return movement of the frame, when the dog falls by gravity to lowered position so as to pass freely under the succeeding blank and is again raised to engage it by the spring 70.

An additional dog 72 is similarly constructed with lugs pivotally engaging one of the rear cross braces 53 of the pusher frame. Shoulder 73 of this dog has a depending stop lug 74 for engagement with the adjacent cross brace 53 and a depending finger 75 for engagement with a similar leaf spring 76 fixed on the frame. This dog is preferably slotted, as at 77, to clear a vertical squaring plate and stripper bars hereinafter described, and it is preferably provided, at opposite sides of this slot, with rearwardly extending fingers 78 arranged to rest upon and hold the downwardly folded side flaps of the blank. The operation of this dog is similar to

that of dog 65, its shoulder 73 and fingers 78 being raised by the spring 16, in the forward position of the frame, for engagement with the forward edges of a blank stationarily positioned at the second folding station. On the rearward movement of the frame, this dog pushes the blank along the guide rails 41 under the presser shoes 49 to discharge it in folded condition from the machine, for delivery to a stitching or taping device, for fastening the downwardly folded side portions together.

The folding stations referred to above are provided in conjunction with a pair of folding frames supported on the main frame, one on each side of the pair of guide rails 41 and slidably movable toward and from the latter to correspond with the width of a blank to be folded. These frames, indicated generally at 79 and 89 (Figs. 1 and 3) preferably comprise horizontal plates and flanges forming platform portions, indicated generally at 81 and 82, each having an inner pair of relatively short corner legs 83 and an outer pair of longer legs 84. All four of these legs have bearing openings for a pair of spaced, transversely extending rods, as 85, fixed at their ends on the main frame to support each folding frame for adjustment in lateral directions. The longer outer legs 84 of each frame have openings threadedly engaged with a lower shaft 83 rotatably supported at its ends in suitable bearings on the main frame, for rotation, by means hereafter described, to laterally adjust the corresponding folding frame.

Each folding frame has along the inner side of its platform an angle-shaped guide rail 87 mounted on uprights 88 carried by the frame and extending parallel with the guide rails 41 and at the same elevation. Each frame has fixed thereto also a brace rod 89 fixed at its other end to the outer end of a tubular sleeve 90 sliding longitudinally on a cross rod 91 fixed at its outer ends to the auxiliary side rails 26. The inner end of each sleeve 90 has fixed thereto a resilient presser shoe in the form of an elongated leaf spring 92 arranged to bear against the upper surface of a blank to hold it on the guide rails 87 of the folding frame. It is apparent from this construction that as each frame is adjusted laterally, its connected sleeve 90 is correspondingly adjusted on rod 91 and adjusts the presser shoe 92 to maintain its position above the corresponding guide rail 87.

A blank to be folded is scored along the lines 93 (Fig. 4) to mark off side portions or flaps 94 to be folded upwardly, inwardly and downwardly about the lines 93, and means are provided at the first folding station for folding these flaps upwardly to substantially vertical position, as shown in Fig. 4, comprising on each folding frame, preferably, a substantially spiral arm 95 fixed on the inner end of a spindle 96 extending horizontally inwardly from a gear housing 97 on the folding frame. The gearing in the housing for rotating these arms is driven by a universally coupled shaft 98 extending forwardly from folding means at the second folding station for folding the flaps 94 inwardly and downwardly against the intermediate body portion of the blank hereafter described. Retainer rods 98a are provided, one on each of the folding frames, for retaining the folded flaps in vertical position while passing to the second folding station, as useful more especially in the folding of short blanks.

At the second folding station each folding

frame carries a gear housing 99 for driving the shaft 98 and also a vertically extending spindle 100 to which is fixed a substantially spiral arm 101. The gearing in each housing 99 is driven by a short shaft 102 connecting it with gearing in a rearward housing 103 on each folding frame, having a short shaft extending horizontally outwardly and carrying a sprocket wheel 104 driven by means hereafter described. As folding arms 101 are rotated in the direction of the arrows by the means described, they smoothly engage and fold the outer side portions or flaps 94 of the blank, from the vertical position of the first folding station, inwardly and downwardly against the body of the blank, as shown in Fig. 4, in conjunction with means for truing or squaring the inwardly folded edges which will now be described.

The means for truing or squaring the flaps 94 as they are folded down against the body of the blank at the second folding station comprises, preferably, a vertical squaring partition or plate 105 (Figs. 2 and 4) having slots 106 at the ends of its upper edge slidably embracing screws 107 carried by a bar 108 on a pair of brackets 109 depending from a housing 110 supported in elevated position above the machine. This housing is mounted at its rear end on inclined struts 111 fixed to the rear end rail of the main frame, with an additional strut 112 extending forwardly and downwardly from the lower front end of the housing and fixed to a sleeve 113 on the supporting rod 91 described above, so as to firmly support the housing. Plate 105 has its lower edge positioned to lie between the adjacent edges of the folded flaps 94, and spaced slightly above the intermediate body portion of the blank, so that the latter may be readily moved beneath it. As the flaps 94 are folded inwardly and downwardly as described, their edges engage and are guided by the opposite sides of the plate which acts to force them into slightly spaced, aligned relation with each other, and means are provided for subsequently stripping the flap edges from the plate so that the blank may be discharged from the machine as will now be described.

The means for stripping the blank edges from the squaring plate 105 comprises, preferably, a pair of stripping bars 114 adapted to slide vertically in close contact with opposite sides of the plate. Preferably, these bars are integrally constructed by forming a single bar of material with a slot closely fitting the opposite sides of the plate, as shown. The stripping bars are fixed on the lower ends of a pair of spaced rods 115 rising vertically at the ends of the plates, respectively, and extending at their upper ends through bearing openings in the bottom of housing 110. Within the housing, the upper ends of the rods 115 are pivotally connected at 116 to short links 117, the other ends of which are pivotally connected at 118 to arms 119 fixed at their other ends to a pair of meshing gears 120, respectively. The gears are rotatably mounted on trunnions supported by a stationary plate 121 in the housing, and one of the gears has fixed thereto also an arm 122 pivoted at 123 to a link 124 pivoted at its other end to an arm 125 fixed inside the housing on the end of the shaft 126 extending through the side of the housing outwardly to one side of the machine and supported for rocking movement by a bearing 127 adjacent the housing and by a bearing 128 at its other end on a brace 129 on the main frame. This outer end of the shaft 126 has fixed thereon an arm 130 pivotally connected

to the upper end of a pitman 131 having its lower end connected to a crank arm 132 on a shaft 133 extending across the rear end of the frame and supported in bearings thereon, as 134.

It is apparent from the above construction that as shaft 133 is rotated by means hereafter described, pitman 131 will rock shaft 126 and the connected link 124 will oscillate the gears 120 to oscillate the arms 119 and uniformly raise and lower rods 115 and the stripping bars 114. These parts are shown in full lines in Fig. 2 in positions corresponding to the raised position of the stripper bars, while the positions shown in dotted lines correspond to the lowered position of the stripper bars. The movements of these parts are so coordinated with that of the blank pusher that dog 12 starts to push a blank out of the machine slightly before edges of the blank flaps 94 are stripped from the squaring plate 105, to effect an improved truing action, as hereafter described.

The means for squaring the infolded flaps preferably comprises also a pair of squaring bars which are positively moved to press against the outside of the line of fold of the flaps, simultaneously with the downward folding of the same against the squaring plate, to positively and accurately confine the bending to the intended folding score line. These bars are shown at 135 (Fig. 1, 2, 3 and 10), fixed on the upper ends of arms 136 pivoted at their lower ends on the respective folding frames. One of these arms of each bar has connected thereto a compression spring 137 connected at its outer end with an arm 138 having its lower end pivotally mounted on the folding frame. Each arm 138 carries a roller 139 engaging a cam 140 fixed on the short shaft 102 which connects the gears in housings 99 and 103. Attached to the arm 138 also is a tension spring 141, the outer end of which is connected by a turnbuckle with the outer rail of the folding frame.

It will be seen from this construction that as shaft 102 rotates, the high portion of its cam will rock arm 138 and, through compression spring 137, will force each squaring bar 135 against the outside of the fold lines in the blank, the action of these parts being so timed that the bars engage the blank as its edges are forced down by the rotary spiral arms 101 into engagement with the squaring plate 94, the folding of the flaps being thus positively confined between opposing surfaces at the edge and fold line of each flap, so that departure of the fold from the folding score line is eliminated and precise folding is assured. The parts are timed so that squaring bars 135 are withdrawn from contact with the fold line at the instant the pusher frame begins its rearward movement. The stripping of the blank edges from the squaring plate 94, by the action of stripping bars 114, is somewhat delayed, as stated, so that the movement of the blank is started while its edges are still in engagement with the plate, as this has been found, under some circumstances, to add to the precision of the operation. If one of the blank flaps has lagged slightly behind so as to present a projecting edge toward the dog, the pressure of the dog tends to push the flap edge ahead and correct the alignment of the flap with the squaring plate, while if the flap is slightly advanced so that the end of its side edge nearest the dog bears more closely against the squaring plate, the movement of the blank imposes a greater frictional drag on the edge of the flap nearest the dog which draws it back into proper position.

The mechanism for driving the blank pusher frame, the folding arms and the stripping and squaring bars comprises, preferably, a pulley 142 on a shaft 143 (Fig. 2), rotating in bearings, as 144, on the main frame and driven by an electric motor (not shown) mounted on an inner lower portion of the frame. Pulley 142 has a belt connection 145 with a pulley 146 fixed on a shaft 147 extending about half way across the main frame (Fig. 3) and supported thereon in bearings 148 and 149, the latter bearing being mounted on a post 150 rising from a rail 151 carried by hanger straps 152 depending from the main frame. Shaft 147 has fixed thereon a sprocket wheel 153 connected by a chain 154 with a sprocket wheel 155 fixed on shaft 133. The latter has splined thereon a pair of sprockets 156 connected by chains 157 with the sprockets 104 on the spindles projecting horizontally from the gear housings 103 for driving the folding arms, as described. An arm 157a depending from each folding frame has a forked lower end engaged in a groove in the hub of splined gear 156 to shift it along shaft 133 as the frame is adjusted toward or from the central guide rails 41.

The inner end of shaft 147 carries a crank arm 158 to which is connected a pitman 159 having its other end pivoted at 160 to a bracket 161 on a rock arm 162 having its lower end pivotally supported in a bearing 163 on the beam 151. The upper end of the rock arm is pivoted at 164 to a rod 165 having its other end pivoted at 166 to a bracket arm 167 fixed on and depending from the blank pushing frame for continuously reciprocating the same as the arm 162 is rocked by crank 158 on the motor driven shaft 147.

The folding frames are preferably adjusted toward and from each other by means comprising a pair of electric motors 168 (Fig. 2) mounted on the underneath portion of the main frame adjacent its front or hopper end and each connected by gearing (not shown) with a short jack shaft 169 having fixed thereon a pulley driving a belt 170. The latter drives a pulley 171 fixed on a transversely extending, threaded shaft 172, corresponding to a shaft 86 at the rear end of the machine, for adjusting the folding frames. Each shaft 172 carries a sprocket (not shown) driving a chain 174 extending longitudinally of the machine and driving a sprocket 175 (Fig. 3) fixed on the shaft 86. It will be seen from this construction that on closing the circuit of motor 168, by any suitable switch means, the threaded shafts 86 and 172 are rotated at the same speed for moving the opposite ends of the folding frame laterally. A similar but separate mechanism is provided for each of the folding frames, and each frame carries a pointer 176 (Fig. 1), moving over a transverse scale 177 adjacent the hopper. The switches controlling the motor 168 are preferably located adjacent the hopper so that the operator at that position can readily adjust the several hopper parts described above, as well as the folding frames, to suit the particular size and shape of the blanks to be folded.

In operation, with the several hopper parts adjusted to the size and shape of the blanks to be folded and the gate fingers set to permit the passage of single blanks, the main driving motor is energized by a switch control (not shown) located adjacent the position of the operator at the hopper. The blank pusher frame is thereby set into continuous reciprocating movement and its dogs feed the lowermost blanks in the stack, one after another, to the successive folding sta-

tions at which the side portions or flaps are first folded upwardly and then inwardly and downwardly on the intermediate portion of the blank. The final downward folding is accomplished at the second folding station, at which the edges of the flaps are folded down against the opposite sides of the squaring plate, to true their folded position, assisted by the squaring bars, which simultaneously press against the outside of the lines of fold and confine the folding accurately to such lines. The latter bars then release the blank, and the pusher frame begins a rearward movement just before the edges of the blank are fully stripped from the squaring plate by the stripper bars. By such positive folding means, the blanks are precisely folded along the score lines, being ejected by the pusher frame for delivery to stitching or taping mechanism, for securing the folded flaps together.

In Fig. 5 is shown a modified construction of squaring plate in which the plate means is constructed in spaced sections, 178 and 179, each adjustably supported as described above in connection with plate 105. The plates are spaced apart a sufficient distance to receive therebetween a stitching lap 180 on a side portion or flap 181 so that it may overlie the opposite side portion or flap 182 for stitching thereto, as well understood in the art. Stripping bars 114, operated by rods 115, are arranged to engage the opposite sides of the spaced plates 178 and 179, as described above in connection with the first modification.

The invention provides a simple and practical machine in which the side portions of the blank are folded by rotating arms while the blanks are stationary at successive folding stations and the blanks are accordingly pushed along their guideways by the application of a minimum amount of force having no tendency to injure the blank material. This movement of the blanks is accomplished by a relatively simple frame of light construction requiring only a crank and pitman for imparting its reciprocating movement. In the final and more difficult step of folding the flaps down flat on the body of the blank, the folded flaps are precisely folded along their score lines between opposing squaring means, which simultaneously engage each flap at both its folding line and its edge, to positively insure precise folding alignment before the blank is delivered to taping or stitching devices for securing the flaps, the machine being adapted to handle blanks intended for either the known taped or stitched lap type of construction. The machine is fully adjustable to a wide variety of sizes and shapes of blanks, the adjusting means being within convenient reach of the operator at the hopper end of the machine, including both the hopper adjusting means and the means for adjusting the folding frames toward and from the line of movement of the blanks. Such advantageous features provide a simple and practical type of machine having a high rate of production and a high degree of precision in the folding of the blanks.

It will thus be seen that the invention accomplishes its objects and while it has been herein disclosed by reference to the details of preferred embodiments, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A box blank folding machine comprising a main frame having a blank receiving station and a plurality of blank folding stations, a guideway on said frame on which the blanks are slidably movable from station to station, means for holding the blanks on said guideway, a blank pusher having a reciprocating movement on said frame, a plurality of dogs movably mounted on said pusher and normally positioned to pass under the blanks during movement of said pusher in one direction, means positioned to engage and raise said dogs at the end of movement in said direction for engaging and moving the blanks along said guideway from station to station during movement of said pusher in the other direction, means having a movement at one of said stations to fold side portions of a blank upwardly while said blank is stationarily positioned at said station, means having a movement at another of said stations to fold said side portions inwardly and downwardly adjacent the body portion of the blank while said blank is stationarily positioned at said other station, and mechanism for operating said pusher and said folding means in timed coordination with one another.
2. A box blank folding machine comprising a main frame having a blank receiving station and a plurality of blank folding stations, a blank pusher having a reciprocating movement on said frame, a plurality of dogs pivoted on said pusher for movement by gravity to position to pass under the blanks during movement of said pusher in one direction, spring means positioned on said frame to engage and raise said dogs at the end of movement in said direction for engaging and moving the blanks from station to station during movement of said pusher in the other direction, means having a movement at one of said stations to fold side portions of a blank upwardly while said blank is stationarily positioned at said station, means having a movement at another of said stations to fold said side portions inwardly and downwardly adjacent the body portion of the blank while said blank is stationarily positioned at said other station, and mechanism for operating said pusher and said folding means in timed coordination with one another.
3. A box blank folding machine comprising a main frame having a blank receiving station and a plurality of blank folding stations, a guideway on said frame on which the blanks are slidably movable from station to station, resilient presser means for holding the blanks on said guideway, a blank pusher having a reciprocating movement on said frame, a plurality of dogs pivoted on said pusher for movement by gravity to position to pass under the blanks during movement of said pusher in one direction, spring means positioned on said frame to engage and raise said dogs at the end of movement in said direction for engaging and moving the blanks along said guideway from station to station during movement of said pusher in the other direction, means having a movement at one of said stations to fold side portions of a blank upwardly while said blank is stationarily positioned at said station, means having a movement at another of said stations to fold said side portions inwardly and downwardly adjacent the body portion of the blank while said blank is stationarily positioned at said other station, and mechanism for operating said pusher and said folding means in timed coordination with one another.
4. A box blank folding machine comprising a

11

main frame having a blank receiving station and a plurality of blank folding stations, a blank pusher having a reciprocating movement on said frame, means on said pusher for engaging and moving the blanks from station to station during movement of said pusher in one direction, a pair of folding frames movably mounted on said main frame for adjustment oppositely toward and from said pusher at each of said folding stations to accommodate blanks of different widths, means movably mounted on said folding frames at one of said stations to fold side portions of the blank upwardly while said blank is stationarily positioned at said station, means movably mounted on said folding frames at another of said stations to fold said side portions inwardly and downwardly toward the body portion of the blank while said blank is stationarily positioned at said other station, and mechanism for operating said pusher and said folding means in timed coordination with one another.

5. A box blank folding machine comprising a main frame having a blank receiving station and a plurality of blank folding stations, a blank pusher having a reciprocating movement on said frame, means on said pusher for engaging and moving the blanks from station to station during movement of said pusher in one direction, a pair of folding frames movably mounted on said main frame for adjustment from opposite sides toward and from said pusher at each of said folding stations to accommodate blanks of different widths, a guideway on each of said folding frames having a presser shoe for holding the blank thereon, means movably mounted on each of said folding frames at one of said stations for folding side portions of the blank upwardly while said blank is stationarily positioned under said presser shoe at said station, means rotatably mounted on said folding frames at another of said stations for folding said side portions inwardly and downwardly toward the body portion of the blank while said blank is stationarily positioned at said other station, and mechanism for operating said pusher and said folding means in timed coordination with one another.

6. A box folding machine comprising a main frame having a blank receiving station and a plurality of blank folding stations, a blank pusher having a reciprocating movement on said frame, means on said pusher for engaging and moving the blanks from station to station during movement of said pusher in one direction, a pair of arms rotatably mounted at one of said stations to fold side portions of a blank upwardly while said blank is stationarily positioned at said station, a pair of arms rotatably mounted at another of said stations to fold said side portions inwardly and downwardly toward the body portion of the blank while said blank is stationarily positioned at said other station, and mechanism for reciprocating said pusher and rotating said folding arms in timed coordination with one another.

7. A box blank folding machine comprising a main frame having a blank receiving station and a plurality of blank folding stations, a blank pusher having a reciprocating movement on said frame, means on said pusher for engaging and moving the blanks from station to station during movement of said pusher in one direction, a pair of folding frames movably mounted on said main frame for adjustment from opposite sides toward and from said pusher at each of said folding stations to accommodate blanks of different widths, a guideway on each of said folding frames

12

5 having a presser shoe for holding the blanks thereon, a pair of arms rotatably mounted on said folding frames at one of said stations to fold side portions of a blank upwardly while said blank is stationarily positioned at said station, a pair of arms rotatably mounted on said folding frames at another of said stations to fold said side portions inwardly and downwardly toward the body portion of the blank while said blank is stationarily positioned at said other station, and mechanism for reciprocating said pusher and rotating said folding arms in timed coordination with each other.

15 8. A box blank folding machine comprising a main frame having a blank receiving station and a plurality of blank folding stations, a blank pusher having a reciprocating movement on said frame, means on said pusher for engaging and moving the blanks from station to station during movement of said pusher in one direction, means having a movement at one of said stations to fold side portions of a blank upwardly while said blank is stationarily positioned at said station, means having a movement at another of said stations to fold said side portions inwardly and downwardly toward the body portion of the blank while said blank is stationarily positioned at said other station, squaring plate means at said other station against which the edges of said side portions are folded from opposite sides for squaring the same, means for stripping said edge portions from said plate means, and mechanism for operating said pusher, folding means and stripping means in timed coordination with each other.

25 9. A box blank folding machine comprising a main frame having a blank receiving station and a plurality of blank folding stations, a blank pusher having a reciprocating movement on said frame, means on said pusher for engaging and moving the blanks from station to station during movement of said pusher in one direction, means having a movement at one of said stations to fold side portions of a blank upwardly while said blank is stationarily positioned at said station, means having a movement at another of said stations to fold said side portions inwardly and downwardly toward the body portion of the blank while said blank is stationarily positioned at said other station, squaring plate means at said other station against which the edges of said side portions are folded from opposite sides for squaring the same, means for stripping said edge portions from said plate means, and mechanism for operating said pusher, folding means and stripping means in timed coordination with each other.

30 40 10. A box blank folding machine comprising a main frame having a blank receiving station and a plurality of blank folding stations, a blank pusher having a reciprocating movement on said frame, means on said pusher for engaging and moving the blanks from station to station during movement of said pusher in one direction, means having a movement at one of said stations to fold side portions of a blank upwardly while said blank is stationarily positioned at said station, means having a movement at another of said stations to fold said side portions inwardly and downwardly toward the body portion of the blank while said blank is stationarily positioned at said other station, vertical squaring means at said other station against which the edges of said side portions are folded from opposite sides, squaring 45 bars movable against said side portions at the line of fold thereof for squaring the same, and mechanism for operating said pusher, said folding means and said squaring bars in timed coordination with one another.

45 50 55 60 65 70 75

13

line of fold thereof to square the same, stripper bars for stripping said edges from said plate means, and mechanism for operating said pusher, folding means and squaring and stripper bars in timed coordination with one another.

11. A box blank folding machine comprising a main frame having a blank receiving station and a plurality of blank folding stations, a blank pusher having a reciprocating movement on said frame, means on said pusher for engaging and moving the blanks from station to station during movement of said pusher in one direction, rotary arms of substantially spiral shape at one of said stations for folding side portions of a blank upwardly while said blank is stationarily positioned at said station, rotary arms of substantially spiral shape at another of said stations for folding said side portions inwardly and downwardly toward the body portion of the blank while said blank is stationarily positioned at said other station, vertical plate means at said other station against which the edges of said side portions are folded from opposite sides, squaring bars movable against said side portions at the line of fold thereof to square the same, and stripper bars for stripping said side portions from said plate means.

12. A box blank folding machine comprising a main frame having a blank receiving station and a plurality of blank folding stations, a blank pusher having a reciprocating movement on said frame, means on said pusher for engaging and moving the blanks from station to station during movement of said pusher in one direction, means having a movement at one of said stations to fold side portions of a blank upwardly while said blank is stationarily positioned at said station, means having a movement at another of said stations to fold said side portions inwardly and downwardly toward the body portion of the blank while said blank is stationarily positioned at said other station, squaring plate means against which the edges of said side portions are folded from opposite sides, squaring bars movable against said side portions at the line of fold thereof to square the same, stripper bars for stripping the edges of said side portions from said plate means, and mechanism for moving said stripper bars to strip said side portions from said plate means during discharge movement thereof by said carrier.

13. A box blank folding machine comprising a main frame having a blank receiving station and a plurality of blank folding stations, a blank pusher having a reciprocating movement on said frame, means on said pusher for engaging and moving the blanks from station to station during movement of said pusher in one direction, means having a movement at one of said stations to fold side portions of a blank upwardly while said blank is stationarily positioned at said station, means having a movement at another of said stations to fold said side portions inwardly and downwardly toward the body portion of the blank while said blank is stationarily positioned at said other station, sectional plate means against which the edges of said side portions are folded from opposite sides to square the folding thereof, said plate means having sections supported on said frame for relative adjustment toward and from each other longitudinally of the path of movement of said blanks for the reception between said sections of a stitching lap on one of said blank side portion edges, stripper bars for stripping the edges of said side portions from said plate means, and mechanism for recipro-

14

cating said pusher and moving said folding means and stripping bars in timed coordination with one another.

14. A box blank folding machine comprising a main frame provided with hopper means having a beam mounted transversely on said frame for adjustment longitudinally thereof, gate means adjustable in height on said beam to retain a stack of blanks in said hopper means except the lowermost blank of said stack, side walls for said hopper means adjustable lengthwise of said beam, a plurality of blank folding stations on said frame, a blank pusher having a reciprocating movement on said frame between said hopper means and folding stations, means on said pusher for engaging and moving the blanks during movement of said pusher in one direction, movably mounted means at said folding stations for folding side portions of a blank upwardly, inwardly and downwardly against the body portion of the blank while said blank is stationarily positioned at said stations, and mechanism for reciprocating said pusher and moving said folding means in timed coordination with one another.

15. A box blank folding machine comprising a main frame provided with hopper means having a beam mounted transversely on said frame for adjustment longitudinally thereof, gate means adjustable in height on said beam in accordance with the thickness of the blanks for retaining the blanks above the lowermost thereof in said hopper means, a plurality of blank folding stations, a guideway on said frame on which the blanks are slidably movable from said hopper means to said folding stations, presser shoe means carried by said adjustable gate means for holding the blanks on said guideway, a blank pusher having a reciprocating movement between said hopper means and folding stations, means on said pusher for engaging and moving the blanks along said guideway during movement of said pusher in one direction, movably mounted means at said folding stations to fold side portions of a blank upwardly, inwardly and downwardly against the body portion of the blank while said blank is stationarily positioned at said stations, and mechanism for reciprocating said pusher and moving said folding means in timed coordination with one another.

16. A box blank folding machine comprising a main frame provided with hopper means provided with a beam mounted transversely on said frame for adjustment longitudinally thereof, hopper side walls adjustable lengthwise of said beam, a pair of folding frames movably mounted on said main frame for adjustment toward and from each other transversely of said main frame, scale pointer means adjacent said hopper means for indicating the adjustments of said hopper side walls and folding frames, a plurality of blank folding stations on said folding frames, a blank pusher having a reciprocating movement between said hopper means and folding stations, means on said pusher for engaging and moving the blanks during movement of said pusher in one direction, means movably mounted on said folding frames for folding side portions of the blank upwardly, inwardly and downwardly against the body portion thereof while said blank is stationarily positioned at said folding stations, and mechanism for reciprocating said pusher and moving said folding means in timed coordination with one another.

17. A box blank folding machine comprising a

15

frame having a guideway and a folding station thereon, an upright squaring partition extending along said guideway intermediate the sides of said station with its lower edge spaced above said guideway, means for feeding blanks successively along said guideway to said station under said edge of said partition, means for folding side portions of a blank inwardly and downwardly about the fold lines therein to press the free edges thereof against opposite sides of said squaring partition, respectively, while said blank is stationarily positioned at said station, a squaring bar for pressing inwardly against the outer side of the fold of each of said portions while the free edge of said portion is pressed against said partition to guide said portion to accurately folded position and confine the folding thereof accurately to said fold line, and mechanism for actuating said feeding means, folding means and squaring bars in timed coordination with one another.

18. A box blank folding machine comprising a frame having a guideway and a folding station thereon, an upright squaring partition extending along said guideway intermediate the sides of said station with its lower edge spaced above said guideway, means for feeding blanks successively along said guideway to said station under said edge of said partition, means for folding side portions of a blank inwardly and downwardly about folding lines therein to press the free edges thereof against opposite sides of said partition, respectively, while said blank is stationarily positioned at said station, a stripper movable along the sides of said partition for pressing said blank edges downwardly and under said partition edge, a squaring bar for pressing inwardly against the outer side of the fold of each of said side portions while the free edge of said portion is pressed against said partition to guide said portion to accurately folded position and confine the folding thereof accurately to said fold line, and mechanism for actuating said feeding means, folding means, stripper and squaring bars in timed coordination with one another.

19. A box blank folding machine comprising a frame having a guideway and a folding station thereon, an upright squaring partition extending along said guideway intermediate the sides of said station with its lower edge spaced above said guideway, reciprocating means for feeding blanks successively along said guideway and locating the same stationarily at said station under said edge of said partition, means for folding side portions of a blank inwardly and downwardly about folding lines therein to press the free edges thereof against opposite sides of said squaring partition, respectively, while said blank is stationarily located at said station, a squaring bar for pressing inwardly against the outer side of the fold of each of said side portions while the free edge of said portion is pressed against said partition to guide said portion to accurately folded position overlying the body of said blank and confine the folding thereof accurately to said fold line, and mechanism for actuating said feeding means, folding means and squaring bars in timed coordination with one another.

20. A box blank folding machine comprising a frame having a guideway and a folding station thereon, an upright squaring partition extending along said guideway intermediate the sides of said station with its lower edge spaced above said guideway, means for feeding blanks successively along said guideway to said station under said edge of said partition, curved arm means for

16

folding side portions of a blank inwardly and downwardly about the fold lines thereof to press the free edges thereof against opposite sides of said squaring partition, respectively, while said blank is stationarily positioned at said station, means for continuously rotating each of said arm means in the same direction, a stripper movable along the sides of said partition for pressing said blank edges downwardly and under said partition edge, a squaring bar for pressing inwardly against the outer side of the fold of each of said side portions while the free edge of said portion is pressed against said partition to guide said portion to accurately folded position and confine the folding thereof accurately to said fold line, and mechanism for actuating said feeding means, arm means, stripper means and squaring bars in timed coordination with one another.

21. A box blank folding machine comprising a frame having a guideway and a folding station thereon, an upright squaring partition extending along said guideway intermediate the sides of said station with its lower edge spaced above said guideway, reciprocating means for feeding a blank successively along said guideway to locate the same stationarily at said station under said edge of said partition, means for folding side portions of a blank inwardly and downwardly about the folding lines therein to press the free edges thereof against opposite sides of said squaring partition, respectively, while said blank is stationarily located at said station, a stripper movable along the sides of said partition for pressing said blank edges downwardly and under said partition edge, a squaring bar for pressing the outer side of the fold of each of said side portions while the free edge of said portion is pressed against said partition to guide said portion to accurately folded position and confine the folding thereof accurately to said fold line, and mechanism for actuating said feeding means, folding means, stripper and squaring bars in timed coordination with one another.

22. A box blank folding machine comprising a main frame having a blank receiving station and a plurality of blank folding stations, blank feeding means having a reciprocating movement on said frame and provided with means for engaging and moving the blanks from station to station, a pair of folding frames movably mounted on said main frame for adjustment oppositely toward and from said feeding means at each of said folding stations to accommodate blanks of different widths, means on said folding frames at one of said stations for folding side portions of the blank upwardly while said blank is stationarily positioned at said station, arms rotatably mounted on said folding frames at another of said stations to fold said side portions inwardly and downwardly adjacent the body portion of the blank while said blank is stationarily positioned at said other station, means for continuously rotating said arms, squaring plate means at said other station against which the edges of said side portions are folded from opposite sides, and mechanism for operating said feeding means and folding arms in timed coordination with one another.

23. A box blank folding machine comprising a main frame having a blank receiving station and a plurality of blank folding stations, a blank feeding means having a reciprocating movement on said frame and provided with means for engaging and moving the blanks from station to station, means at one of said stations for folding

17

side portions of a blank upwardly while said blank is stationarily positioned at said station, a pair of arms rotatably mounted at another of said stations to fold said side portions inwardly and downwardly adjacent the body portion of the blank while said blank is stationarily positioned at said other station, means for continuously rotating said folding arms, and mechanism for reciprocating said feeding means and rotating said folding arms in timed coordination with one another. 10

24. A box blank folding machine comprising a main frame having a blank receiving station and a plurality of blank folding stations, a blank feeding means having a reciprocating movement on said frame and provided with means for engaging and moving the blanks from station to station, means at one of said stations for folding side portions of a blank upwardly while said blank is stationarily positioned at said station, a 20 pair of arms rotatably mounted at another of said stations to fold said side portions inwardly and downwardly adjacent the body portion of the blank while said blank is stationarily positioned at said other station, means for continuously rotating said folding arms, squaring plate means at said other station against which the edges of said side portions are folded from opposite sides, and mechanism for operating said feeding means and rotating said folding arms in 30 timed coordination with one another.

25. A box blank folding machine comprising a frame having a guideway and a folding station

18

thereon, an upright squaring partition extending along said guideway intermediate the sides of said station with its lower edge spaced above said guideway, means for feeding blanks successively along said guideway to said station under said edge of said partition, means for folding side portions of a blank inwardly and downwardly about the fold lines therein to press the free edges thereof against opposite sides of said squaring partition, respectively, while said blank is stationarily positioned at said station, means for engaging and holding the outer side of the fold of each of said portions while the free edge of said portion is pressed against said partition to guide said portion to accurately folded position and confine the folding thereof accurately to said fold line, and mechanism for actuating said feeding means and folding means in timed coordination with one another.
